UNITED STATES PATENT OFFICE.

WILLIAM H. MAHLER, OF NEWARK, NEW JERSEY.

CHEMICAL APPARATUS.

1,405,733.

Specification of Letters Patent. Patented Feb. 7, 1922.

Application filed May 25, 1918, Serial No. 236,512. Renewed April 26, 1921. Serial No. 464,535.

To all whom it may concern:

Be it known that I, WILLIAM H. MAHLER, a citizen of the United States, residing at Newark, county of Essex, State of New Jersey, have invented certain new and useful Improvements in Chemical Apparatus, of which the following is a specification.

This invention relates to chemical apparatus.

10 More particularly this invention relates to chemical apparatus for effecting the hydrogenation or reduction of organic compounds for deriving benzidine from nitrobenzol or its homologues.

15 A preferred form of my invention comprises a movable container provided with suitable mounting means, and having a charging and discharging opening, provided with a liquid-tight closure, shelves arranged 20 interiorly of the movable container and extending more or less transversely to the direction of movement of the movable container, and agitating means movable upon the movement of the movable container and 25 extending more interiorly thereof relatively to the shelves. In the most preferred form of my invention, the movable container is a cylindrical drum, mounted in bearings to be rotated. A discharge piping for removing 30 the gases ensuing in the treatment may be provided, extending through one of the bearings. A recording thermometer preferably of the pyrometer type, is arranged to indicate the progress and termination of the 35 respective stages of the treatment.

Other features and objects of the invention will be more fully understood from the following description and the accompanying drawings, in which

40 Fig. 1 is a central vertical section of one form of my invention; and

Fig. 2 is a transverse section on the line 2—2 of Fig. 1.

Referring to the drawings, the drum 1, of 45 steel or the like, is provided at a circular end 2 with the trunnion 3 carrying the pulley or gear 4, said trunnion being mounted in the bearing 5. At the opposite circular end 6 of the drum 1 may be provided the hollow 50 trunnion 7 mounted in the bearing 9, the open end of the trunnion communicating in gas-tight relation with the gas exhaust passage 10, discharging as desired, into a flue, washer or the like. The bearings of the

drum are preferably of the roller bearing type.

Interiorly of the drum are arranged the shelves 11 extending more or less radially, said shelves 11 being fixed on the inner part substantially in planes passing through the 60 axis of the drum 1. Coacting with said shelves 11 are arranged a plurality of open-faced agitating members 12 extending toward the axis of the drum more interiorly as compared with the shelves 11. The 65 shelves 11 may be perforated, if desired.

Preferably, the agitating members 12 are disposed in sets or series affixed to the respective shelves 11 and preferably in zig-zag or staggered relation to one another. 70 Thus, in the drawings, I have indicated alternate sets of two and three members extending radially with respect to the successive shelves, the number of members in the respective sets being chosen in accordance with the desired degree of agitation. 75

The indicator 13 is connected by suitable circuit leads 14 with the pyrometer 15 positioned within the drum 1. In my co-pending application Serial Number 236,511, filed 80 by me on May 25, 1918, entitled Method of deriving benzidine and its homologues, I have set forth a new and useful method of deriving benzidine or its homologues, by charging an aqueous mixture of nitrobenzol, 85 caustic soda and zinc in either granular, flake or feather form. The proportional parts of the aforesaid ingredients by weight are, in the order named, 123, 50 and 200, with approximately 300 parts by weight of 90 water.

The water may be first charged, then the caustic soda is added; then the nitrobenzol is poured in and finally the full amount of zinc in granular, flake or feather form is 95 charged, preferably distributing the zinc as uniformly as possible on the bottom of the interior of the drum.

The entire charge should, preferably, not extend more than one-third of the vertical 100 height of the drum.

The charging is made through the opening 18, which is provided with the gas and liquid-tight closure 19.

The drum is now rotated by suitable driving means, at a speed of say from 15 to 20 R. P. M. The reaction of the zinc particles and the caustic soda results in the gradual

and continuous evolution of nascent hydrogen, with the development of heat of sufficient amount to provide for its own reaction temperature, without any supplemental heat supplying means.

The proportional yield is increased by coating the drum with asbestos or like heat insulating material, and, also, by enclosing the whole apparatus in a wooden housing.

10 The rotation of the drum continuously raises the zinc in the direction of rotation and also the heavier contents of the charge, which drop back into the mass, continuously repeating the thorough agitation of all portions of the mass as the drum rotates.

15 The complete reduction or hydrogenation of the nitrobenzol takes place in a period of from fourteen to eighteen hours, and personal attention to the apparatus or for feeding the zinc or other ingredient of the charge is entirely eliminated. The indicator card shows by a fall of temperature, say below 50° C. when the reaction has been completed.

20 The evolved gases are conducted through 25 the piping 10 to the atmosphere or through a washer, or otherwise.

25 A particular advantage of my invention is the thorough agitation or circulation throughout the reaction period of the whole 30 of the charge, enabling the whole zinc content of the charge to be fed in at one time; also, in rendering possible the use of granular or flake or feather zinc instead of zinc dust, as necessitated in accordance with prior 35 proposals. The attendance of an operator is obviated entirely, after charging and initiating the rotation of the drum.

40 The resulting hydrazobenzol and accompanying final products are discharged from the drum through the opening 18, and the hydrazobenzol is separated in the usual way from the accompanying reaction products.

45 The agitation members 12 extend preferably considerably more centrally or otherwise toward the center of the drum than the shelves 11, the latter serving to more or less bodily and uniformly raise the zinc particles and heavier liquid content of the charge and the members 12 effecting in cooperation, up to 50 on the rotation of the drum, a complete agitation of the whole mass of the charge.

55 The members 12, as shown, are preferably open or perforated intermediately to thereby enhance the agitation of the contained charge.

60 In a commercial embodiment of my invention, the length of the drum may be five feet, the diameter six feet; the radial height of the shelves not to exceed six inches and the 65 radial height of the apex of each agitating member not to exceed two feet.

65 It will be understood that by the use of the term "cylindrical" I include all forms of polygonal contour.

65 By means of my apparatus the entire zinc

content of the charge is made available for use as the reaction proceeds, and is also beneficial to man-kind in obviating the dissemination of zinc into the atmosphere and impairing the health of the operator, causing 70 illness and often death, as ensues in the use of methods and apparatus heretofore employed.

Whereas I have described my invention by reference to specific forms thereof, it will 75 be understood that many changes and modifications may be made without departing from the principle of the invention as defined by the appended claims.

I claim.

1. The combination with a movable container adapted to receive a charge of chemically interacting substances, means for indicating the temperature of the interior of the container, means for elevating within the interior of the container the relatively heavier substances of the charge and returning the same into the charge comprising a plurality of spaced, relatively narrow shelves disposed within said container, each said shelf extending longitudinally substantially parallel to the direction of length of said container and substantially continuously from one end to the other end of said container, each said shelf having an edge engaging the inner face 95 of said container, each said shelf extending inwardly toward the center of said container, and spaced agitation members disposed within said container extending inwardly and more closely to the center of the interior 100 of said container than said shelves.

2. The combination of a substantially cylindrical container adapted to receive a charge of chemically interacting substances; means for indicating exteriorly of the container the 105 temperature of the interior of said container; means for elevating within the interior of said container the relatively heavier substances of the charge and returning the same within the charge comprising a plurality of spaced, 110 relatively narrow shelves disposed within said container, each said shelf extending longitudinally substantially parallel to the axis of the said container and substantially continuously from one end to the other end 115 of said container, each said shelf having an edge engaging the inner cylindrical face of said container, each said shelf extending inwardly toward the center of said container; spaced agitation members disposed 120 within said container extending inwardly and more closely to the center of said container than said shelves and means for moving said shelves and said agitation members.

3. The combination of a substantially cylindrical container adapted to receive a charge of chemically interacting substances; means for indicating exteriorly of said container the temperature of the interior of said con- 130

- tainer; means for elevating within the interior of said container the heavier substances of the charge and returning the same within the charge comprising a plurality of spaced, 5 relatively narrow shelves fixed to the inner cylindrical face of said container, each said shelf having a longitudinal edge engaging the inner cylindrical face of said container; each said shelf extending inwardly toward the center of said container and longitudinally substantially continuously from one end to the other end of said container and substantially parallel to the axis of said container; spaced agitation members mounted 10 interiorly of said container and extending inwardly more closely toward the center of said cylinder than said shelves; and means for rotating said cylinder and therewith said shelves and said agitation members.
- 15 4. The combination of a rotatable cylindrical container having a charging and discharging opening, liquid-tight closure means for said opening, a plurality of spaced shelves disposed on the inner cylindrical surface of the container, and means for rotating said container, each said shelf extending longitudinally from one end of said container to the other end and inwardly toward the center of said container.
- 20 5. The combination of a rotatable cylindrical container, having a charging and discharging opening, liquid-tight closure means for said opening, a plurality of spaced shelves disposed on the inner cylindrical surface of the container, each said shelf extending longitudinally substantially continuously from one end to the other of said container and substantially parallel to the axis of said container, a plurality of agitation members extending between said shelves and the center of the container and means for rotating said container.
- 25 6. The combination of a rotatable cylindrical container having a charging and discharging opening, liquid-tight closure means for said opening, a plurality of spaced shelves disposed on the inner cylindrical surface of the container, each said shelf extending longitudinally substantially continuously from one end to the other end of said container and substantially parallel to the axis of said container, a plurality of spaced, recessed agitation members extending between said shelves and the center of the container and means for rotating said container.
- 30 7. The combination of a hollow drum, trunnions carried at the opposite circular ends of said drum, bearings for said trunnions, one of said trunnions being hollow, a discharge piping in gas-tight relation to said hollow trunnion, said drum having a charging and discharging opening, a liquid-tight closure for said opening, spaced shelves disposed on the inner cylindrical surface of
- 35 said drum and extending radially inwardly and longitudinally of said drum substantially parallel to the axis of the drum, recessed agitation members extending from said shelves respectively towards the center of the drum, said members being staggered relatively to one another and means for rotating said drum.
- 40 8. The combination of a substantially cylindrical container adapted to receive a charge of chemically interacting substances; means for indicating exteriorly of said container the temperature of the interior of said container; means for elevating within the interior of said container the relatively heavier substances of the charge and returning the same within the charge comprising a plurality of spaced, relatively narrow shelves fixed to the inner cylindrical face of said container, each said shelf having a longitudinal edge engaging the inner cylindrical face of said container; each said shelf extending inwardly toward the center of said container and longitudinally substantially continuously from one end to the other end of said container and substantially parallel to the axis of said container; spaced agitation members mounted interiorly of and fixed to said container and extending inwardly more closely toward the center of said cylinder than said shelves; and means for rotating said cylinder and therewith said shelves and said agitation members.
- 45 9. The combination of a substantially cylindrical container adapted to receive a charge of chemically interacting substances, one end of said container being provided with an opening, means for rotatably mounting said container, passage means communicating with said opening; means for indicating exteriorly of said container a temperature of the interior of said container; means for elevating within the interior of said container the relatively heavier substances of the charge and returning the same within the charge comprising relatively narrow shelves extending longitudinally substantially parallel to the axis of said container, each said shelf having its outward longitudinal edge fixed to and engaging the inner face of said container, each said shelf extending toward the center of said container and spaced agitation members respectively mounted on the inward longitudinal edges of said shelves.
- 50 10. The combination of a cylindrical container, one end of said container being provided with an opening, means for rotatably mounting said container, passage means communicating with said opening; relatively narrow shelves extending longitudinally substantially parallel to the axis of said container, each said shelf having its outward longitudinal edge fixed to and engaging the inner face of said container, each

said shelf extending toward the center of said container and spaced agitation members respectively mounted on the inward longitudinal edges of said shelves, each said agitation member being interiorly recessed.

11. The combination of a cylindrical container, one end of said container being provided with an opening, means for rotatably mounting said container, passage means 10 communicating with said opening; relatively narrow shelves extending longitudinally substantially parallel to the axis of said container, each said shelf having its outward longitudinal edge fixed to and engaging 15 the inner face of said container, each said shelf extending toward the center of said container and spaced agitation members respectively mounted on the inward longitudinal edges of said shelves, said agitation 20 members being disposed in staggered relation to one another.

12. The combination of a cylindrical container, one end of said container being provided with an opening, means for rotatably 25 mounting said container, passage means communicating with said opening; relatively narrow shelves extending longitudinally substantially parallel to the axis of said container, each said shelf having its 30 outward longitudinal edge fixed to and engaging the inner face of said container, each said shelf extending toward the center of said container and spaced agitation members respectively mounted on the inward longitudinal 35 edges of said shelves, said agitation members being interiorly recessed and disposed in staggered relation to one another.

13. The combination with a movable container adapted to receive a charge of solid 40 and liquid constituents, said container being provided with means for retaining the solid and liquid constituents of the charge; means for discharging the gases evolved by chemical action upon movement of the container; said container being further provided with a charging opening and a removable fluid-tight closure for said charging opening; means for elevating within the interior of said container the relatively 45 heavier constituents of the charge and re-

turning the same within the charge comprising a plurality of spaced, relatively narrow shelves disposed within said container on said shelf extending longitudinally substantially parallel to the direction of length 55 of said container and substantially continuously from one end to the other end of said container, each said shelf having an edge engaging the inner cylindrical face of said container, each said shelf extending inwardly toward the center of said container; spaced agitation members disposed within said container extending inwardly and more closely to the center of said container than said shelves and means for moving said 60 shelves and said agitation members.

14. The combination of a substantially cylindrical container adapted to receive a charge of chemically interacting solid and liquid constituents, said container being 70 provided with means for retaining the solid and liquid constituents of the charge; means for discharging the gases evolved by chemical action upon movement of said container, said container being further provided with 75 a charging opening and a removable fluid-tight closure for said charging opening, means for elevating within the interior of said container the relatively heavier constituents and returning the 80 same within the charge comprising a plurality of spaced, relatively narrow shelves fixed to the inner cylindrical face of said container, each said shelf having a longitudinal edge engaging the inner cylindrical face of said container; each said shelf extending inwardly toward the center of said container and longitudinally substantially 85 continuously from one end to the other end of said container and substantially parallel to the axis of said container; spaced agitation members mounted interiorly of said container and extending inwardly more closely toward the center of said cylinder than said shelves; and means for rotating 90 said cylinder and therewith said shelves and said agitation members.

In testimony whereof I have signed this specification this 23rd day of May, 1918.

WILLIAM H. MAHLER.
